(57) **CLAIM**

The ornamental design for a kitchen utensil, as shown and described.

DESCRIPTION

FIG. 1 is a perspective view of a kitchen utensil design showing my new design;

FIG. 2 is a right side view of the kitchen utensil thereof;

FIG. 3 is a front view of the kitchen utensil thereof;

FIG. 4 is a rear view of the kitchen utensil thereof;

FIG. 5 is a top plan view of the kitchen utensil thereof; and,

FIG. 6 is a bottom plan view of the kitchen utensil thereof.

The kitchen utensil (“kitchen utensil”) is characterized by utensil combination of a peeler, a poker and a bruise remover for a potato or other comestible item.
